COLLAPSIBLE SLED

Filed July 27, 1928

INVENTOR.
LESTER T. CLARKE

BY *John P. Pollock*
ATTORNEY

UNITED STATES PATENT OFFICE

LESTER J. CLARKE, OF NEW YORK, N. Y.

COLLAPSIBLE SLED

Application filed July 27, 1928. Serial No. 295,660.

This invention relates generally to sleighs and has more particular reference to a novel foldable sleigh.

The invention has for an object the provision of a device of the class mentioned, which is of simple durable construction, desirable and efficient in action, and which can be manufactured and sold at a reasonable cost.

10 Customarily sleighs are built so that the front portions of its runners may be flexed to one side or the other for steering purposes. The front portions of sleigh runners are bent upwards and this materially interferes with flexing these fronts, and consequently steering is highly inefficient. This invention proposes the use of runners with exceptionally long and free rear portions for adaption to ease in flexing. Then these rear 15 portions may be flexed for steering purposes, which arrangement contributes to efficient steering. A chair is attached to the fronts of the runners, and arranged for folding, and for adjustments of the chair back and the 20 seat for suiting the comfort tastes of a user. 25

For further comprehension of the invention, and of the object and advantages thereof, reference will be had to the following description and accompanying drawings, and 30 to the appended claims in which the various novel features of the invention are more particularly set forth.

In the accompanying drawing, forming a material part of this disclosure:

35 Fig. 1 is a perspective view of a device constructed according to this invention.

Fig. 2 is a plan view thereof.

Fig. 3 is a rear view thereof.

Fig. 4 is a fragmentary vertical sectional 40 view, taken on the line 4—4 of Fig. 1.

Fig. 5 is a fragmentary vertical sectional view, taken on the line 5—5 of Fig. 4.

Fig. 6 is a fragmentary perspective detail view of a portion of the front legs of the chair.

45 The reference numeral 10 indicates generally a pair of parallel runners having upwardly bent front ends 11. Brackets 12 are secured on these front ends, and a bumper 13 is attached on the brackets.

50 A pair of parallel chair back rods 14 are

pivottally attached at their lower ends to the runners near the front portions thereof for providing long rear portions of the runners, and a top bar 15 is secured between the top ends of the rods 14. Handles 16 are connected 55 on the outer top sides of the rods 14. An intermediate brace rod 17 is fixed between the rods 14, and a lower seat support rod 18 is adjustably secured between the rods 14. The rods 14 are formed with grooves 19 in which 60 the enlarged ends 20 of the rod 18 are slidably arranged for permitting adjustments of the position of the rod 18. A plurality of threaded apertures 21 are formed in the rods 14, and set screws 22 engage in the apertures and 65 set against the enlarged ends 20 for locking the rod 18 in adjusted position.

Chair front legs 23 are pivotally connected at their lower ends onto the runners 10, and are provided with a bar 24 attached between 70 their free ends. A groove 25 is formed in the bottom of the bar 24, for engaging the rod 18. Seat support bars 26 are attached to the inner sides of the legs 23, and seat strips 27 are secured on the support bars 26. 75

Eye members 28 project from the bar 24 and clamp members 29 are pivotally connected as at 30 on the bar and engage over the eye members so as to clamp the bar 24 onto the rod 18. Pegs 31 are passed thru the eyes 80 28 for holding the clamp members 29 in closed position.

The leg members 23 are each formed of separate sections 32 and 33, and section 32 has a reduced end 34 engaging in an aperture 85 35 in the section 32. A wing set screw 36 passes thru an elongated aperture 37 in section 33 for locking the reduced end 34 in desired extended positions.

In operation of the device, one person sits 90 on the seat strips 27, and a second person stands on the rear portions of the runners 10 and holds the handles 16. For propelling the device, the second person removes one foot from one of the runners 10 and pushes 95 with this foot against the ground. For steering, the second person rests with one foot on one runner, and with the other foot bends the other runner.

The tilt of the rods 14 may be changed 100

by an adjustment of the lengths of the legs 23 by reason of the set screws 36, and the tilt of the seat may be changed by adjusting the position of rod 18. The device may be 5 folded by removing the pegs 31, and then disengaging the clamps 29 so that the seat back may be swung down against the runners, and the seat also swung down against the runners.

10 While I have shown and described the preferred embodiment of my invention, it is to be understood that I do not limit myself to the precise construction herein disclosed and the right is reserved to all changes and modifications coming within the scope of the invention as defined in the appended claims.

Having thus described my invention what I claim as new and desire to secure by United States Letters Patent is:

20 1. In a device of the class described, comprising a pair of runners, upright seat back rods pivotally connected at their lower ends to said runners, a transverse bar supported between said rods, rear leg sections having 25 reduced forward ends, the rear ends of said sections attached to said bar, seat strips carried on said sections, and front leg sections also pivotally attached to said runners and having apertures in their rear ends for adjustably receiving the reduced ends of said 30 rear leg sections, the length of the combined leg sections being therefore adjustable for varying the tilt of said upright seat back rods.

35 2. In a device of the class described, comprising a pair of runners, practically vertically disposed seat back rods pivotally connected at their lower ends to said runners, a transverse bar supported between said rods, 40 chair front legs comprising rear sections having reduced forward ends, the rear ends of said sections attached to said bar, seat strips carried on said sections adjacent the seat back rods, front leg sections also pivotally 45 attached to said runners and having apertures in their rear ends for slidably receiving the reduced ends of said rear leg sections, said chair front legs being therefore longitudinally adjustable for varying the tilt 50 of said vertically disposed seat back rods, and wing screws in said front leg sections for holding the reduced ends of said rear leg sections in said apertures.

55 3. In a device of the class described, comprising a pair of runners having upwardly turned front ends, chair front legs pivotally connected at their forward ends to said upwardly turned ends, strips supported on the rear portions of said legs and forming a chair 60 seat, a bar having a groove in the bottom face thereof attached to the rear ends of said front legs, seat back rods also pivotally attached to said runners and having opposed grooves in their inner faces, said seat back 65 rods having threaded apertures therein, a

seat support rod having enlarged ends slidably mounted in the opposed grooves of said seat back rods, said seat support rod seated in the groove of said bar, and a pair of set screws in the threaded apertures of said seat back rods for engaging the enlarged ends of said seat support rod in selected positions to vary the tilt of said chair seat.

In testimony whereof I have affixed my signature.

LESTER J. CLARKE.
